Patented Dec. 16, 1919.

2 SHEETS—SHEET 1.

FIG. 1.

The image contains three technical drawings. The top drawing, labeled 'FIG. 4.', shows a vertical assembly with a central shaft. Various parts are labeled with numbers: 41, 44, 45, 40, 38, 37, 35, 36, 32, 17, 19, 22, 48, 50, 49, 33, 32, 11, 27, 26, 13, 20, 30, 28, 19, 23, 51, 10, and 1. The middle drawing, labeled 'FIG. 5.', is a detailed view of a wheel assembly. It shows a circular wheel with radial spokes, labeled 53 and 52. The bottom drawing, labeled 'FIG. 6.', shows a side view of a component with a ribbed base, labeled 1, 10, and 11. The entire set of drawings is enclosed in a large bracketed area.

UNITED STATES PATENT OFFICE.

GEORGE E. FRANKLIN, OF DETROIT, MICHIGAN, ASSIGNOR OF ONE-THIRD TO JOSEPH TRANCKED AND ONE-THIRD TO FRANK E. HOSKINS, BOTH OF DETROIT, MICHIGAN.

COMBINATION MANIFOLD AND CARBURETER.

1,324,806.

Specification of Letters Patent. Patented Dec. 16, 1919.

Application filed November 13, 1917. Serial No. 201,834.

To all whom it may concern:

Be it known that I, GEORGE E. FRANKLIN, a citizen of the United States, residing at Detroit, in the county of Wayne and State 5 of Michigan, have invented certain new and useful Improvements in Combination Manifolds and Carbureters, of which the following is a specification.

My invention relates to new and useful 10 improvements in manifolds for internal combustion engines and has for its primary object the provision of a manifold which will also serve as a carbureter.

Another object of equal importance with 15 the foregoing is the construction of a manifold in such a manner that it will operate both as the intake and as the exhaust manifold for the engine.

In this connection a still further object 20 of my invention resides in providing a manifold having a passage for exhaust gases and a passage for the explosive mixture and to so arrange them that the passage for the explosive mixture will be adjacent that for 25 the exhaust gases so that the heat of the exhaust gases will assist in vaporizing and preheating the explosive mixture.

Another object consists in providing a 30 spray nozzle structure for supplying liquid fuel into the manifold so disposed that the fuel is drawn from the nozzle into a duct disposed within the exhaust passage, being later drawn from this duct into the fuel passage of the manifold.

Another object resides in drawing air for 35 the explosive mixture into the same duct into which the fuel is drawn and from a point between the manifold and engine casing so that the air supplied is highly heated.

With these and other objects in view, 40 my invention will be more fully described, illustrated in the accompanying drawings and then specifically pointed out in the claims which form a part of this application.

In the drawings:

Figure 1 is a side elevation of a conventional form of engine showing my manifold applied thereto;

Fig. 2 is a horizontal sectional view particularly showing the manner in which the device is secured in position upon the engine.

Fig. 3 is a vertical sectional view taken on the line 3—3 of Fig. 2, looking in the direction of the arrows;

Fig. 4 is a vertical sectional view taken on the line 4—4 of Fig. 3, looking in the direction of the arrows.

Fig. 5 is a fragmentary rear elevation.

In order to insure a clear and accurate understanding of my invention, its application and operation, I have illustrated it in connection with a conventional form of internal combustion engine 10 of the type employed on Ford automobiles.

This engine is of the L-head type having its inlet and exhaust ports all disposed at the same side of the engine casing in the manner shown best in Fig. 2 in which the 70 inlet ports are indicated by the numeral 11 and the exhaust ports by the numeral 12. As there shown, the exhaust ports for the two central cylinders are disposed adjacent each other while the inlet ports for the two 75 front cylinders and the inlet ports for the two rear cylinders are disposed at the front and rear of these exhaust ports. The exhaust ports for the front and rear cylinders being disposed at the front and rear of the inlet 80 ports 11.

My improved manifold includes a main casting or body 13 which is preferably of uniform height throughout its length and which has its inner wall formed with ports 85 14 disposed to register with the inlet ports 11 and with ports 15 disposed to register with the exhaust ports 12. These ports are preferably surrounded by flanges or bosses 16 so that the main body of the manifold 90 will be spaced somewhat from the engine casing when it is in place.

The manifold through that portion of its length lying between the inlet ports 14 is thickened as indicated at 17, and a partition 95 wall 18 separates this thickened portion from the main body of the manifold so that a continuous exhaust passage 19 is provided through out the entire length of the main body of the manifold and an inlet passage 100 20 is provided in the thickened portion, the two being shut-off from each other. The ports 15 lead directly into the exhaust passage 19, while ducts 21 establish communication between the ports 14 and the inlet 105 passage 20.

Midway between the exhaust ports of the manifold which register with the exhaust ports of the central cylinders of the engine the back wall of the manifold is formed with 5 an air inlet port 22 which communicates with the intake passage 20 through a duct 23 which leads through the exhaust passage 19. As shown in Fig. 4 these various ducts are of such diameter as to afford plenty of space 10 above and below them for escape of exhaust gases through the passage 19. The main body of the manifold is, of course, closed at one end and at its other end is adapted in any suitable manner, as indicated at 24, for 15 connection with the usual exhaust pipe 25. Furthermore, at suitable intervals sleeves 26 extend completely through the manifold to receive the shanks of the bolts 27 which are passed through the sleeves and threaded into 20 the usual bolt receiving openings of the engine casing, these bolts replacing the ordinary clamp securing bolts employed with the manifolds now in use.

A jet nozzle pipe 28 is directed upwardly 25 through the main body of the manifold with its upper end disposed substantially centrally of the intake duct 23 and this upper end, as best shown in Fig. 3, is formed to provide a frusto-conical valve seat 29. A 30 needle valve 30 has its stem 31 passed through a suitable stuffing-box 32 on the top wall of the manifold and through the laterally directed arm 33 of a bracket 34 which is preferably secured to the manifold. A 35 helical spring 35 bears between the arm 33 of the bracket and a pin 36 or other abutment carried by the valve stem to normally hold the needle valve in closed position. The stem 31 also passes through a slot in 40 one arm of a bell-crank lever 38, which is pivoted to the bracket 34, and carries nuts 39 by which the valve may be adjusted. A draw-rod 40 is pivoted at one end to the free 45 arm of the lever 38 and projects through the dash 41 of the vehicle, terminating in any convenient form of handle 42. Secured to the dash, preferably within the hood of the vehicle, is a bracket 43 having a series of spaced notches 44 adapted to receive a laterally projecting pin or abutment 45 carried by the rod 40. By pulling this rod and seating its pin 45 in one or the other of these notches the valve may be opened to any desired extent and held in such position. 50 A fuel supply pipe 46 leads from the nozzle pipe 28 to any suitable source of fuel supply such as the tank 47.

A butterfly throttle valve 48 is interposed 55 in the conduit 23 between its outer end and the needle valve and its stem 49 projects through the manifold and carries a lever 50 for connection with any suitable controlling mechanism so that the throttle valve may be controlled from the steering wheel 60 or by a foot-pedal as is usually the custom.

Preferably the outer end of the duct or conduit 23 is closed by a disk 51 of sheet metal or equivalent material cut and stamped out to provide a series of radial openings 52 for the passage of air and adjacent deflector 70 blades 53 tilted to cause air entering through the plate to assume a whirling path so that it will more effectively take up the liquid fuel from the jet nozzle and mix with it.

From the foregoing description, taken in 75 connection with the drawings, the operation of my combined manifold and carburetor will be readily understood. When starting the engine the pull rod 40 is drawn to seat the pin 45 in a notch which will hold the 80 valve 30 fully open so that rich mixture may be assured. Upon cranking the engine the suction of the engine cylinders will draw air into the intake duct 23 through the space between the port 22 and the engine casing 85 and so past the jet nozzle 28 into the intake passage 20, taking liquid fuel with it. This air and fuel will be mixed in the passage 20 and will be drawn from this passage into the engine cylinders in the same manner in 90 which it is drawn from an ordinary intake manifold. After the engine has been in operation a short time the rod may be released and the valve 30 partially closed as a weaker mixture will then be sufficient. By providing a suitable number of notches 44 any desired delicacy of adjustment for the valve may be obtained.

Of course, the supply of air through the intake conduit 23 and consequently the supply of liquid fuel and of explosive mixture to the engine is governed by manipulation of the throttle valve in the usual manner. It should be noted that the fan plate partially closing the opening of this passage 105 serves to agitate the air entering the passage so that it will mix more intimately with the liquid fuel.

Obviously, as soon as the engine has been 110 running for a short time the entire manifold, which is preferably cast or otherwise formed as a single piece, will become highly heated so that both the air and fuel admitted to it will be heated and the explosive mixture formed will be highly heated before it 115 passes to the engine cylinders. This is particularly true due to the fact that the ducts leading from the inlet passage of the manifold to the inlet chambers of the engine pass through the exhaust passage and are, 120 therefore, exposed to the heat of the exhaust gases.

Although the manifold illustrated is particularly designed for use with Ford engines it will, of course, be appreciated that with 125 slight structural changes it may be adapted for use with all engines of the L-head type. I, therefore, reserve the right to make any changes which may be desirable and which fall within the scope of the claims.

Having thus described the invention, what is claimed as new is:

1. A structure for the purpose specified including a body providing an exhaust passage and an intake passage and having a wall thereof formed with ports to register with the ports of an engine, the exhaust passage communicating with certain of the ports and the intake passage communicating with certain other of the ports, and means for admitting fuel mixture to the intake passage and opening through the wall of the body provided with said ports.
2. A structure for the purpose specified including a body providing an exhaust passage and an intake passage and having a wall thereof formed with ports to register with the ports of an engine, certain of said ports opening directly into the exhaust passage, ducts establishing communication between certain other of the ports and the intake passage, and an intake duct leading through the exhaust passage to the intake passage and opening through said wall of the body.
3. A structure for the purpose specified including a body providing an exhaust passage and an intake passage and having a wall thereof formed with ports to register with the ports of an engine, the exhaust passage communicating with certain of the ports and the intake passage communicating with certain other of the ports, an intake duct opening through said wall of the body and communicating with the intake

passage, and means for supplying a fuel mixture within the intake duct.

4. A structure for the purpose specified including a body providing an exhaust passage and an intake passage and having a wall thereof formed with ports to register with the ports of an engine, the exhaust passage communicating with certain of the ports and the intake passage communicating with certain other of the ports, an intake duct opening through said wall of the body and communicating with the intake passage, means for supplying a fuel mixture within the duct, and means for controlling air flow through said duct.

5. A structure for the purpose specified including a body providing an exhaust passage and an intake passage and formed in one side thereof with ports to register with the ports of an engine, the exhaust passage communicating with certain of the ports and the intake passage communicating with certain other of the ports, and means for admitting fuel mixture to the intake passage from the side of the body provided with said ports.

6. The combination with a manifold having an intake passage and provided with an intake duct communicating with said intake passage, of a fuel supply pipe projecting into the intake duct, and manually operable means for controlling the flow of fuel through said pipe.

In testimony whereof I affix my signature.
GEORGE E. FRANKLIN.
